BEER TAP HANDLE

Richard H. Van Den Berg, Milwaukee, Wis., assignor to
Dimensional Products, Inc., Milwaukee, Wis., a corporation of Wisconsin

Filed Feb. 5, 1960, Ser. No. 59,284

Term of patent 14 years

(Cl. D2—3)

FIG. 1

FIG. 2

FIG. 3

FIG. 4

Fig. 1 is an end elevational view of a beer tap handle, showing my new design;

Fig. 2 is a side elevational view thereof, the opposite side being the same in appearance as indicated in Fig. 4;

Fig. 3 is a top plan view of the beer tap handle; and

Fig. 4 is an end view partly in cross-section, taken on the line 4—4 of Fig. 2.

I claim:

The ornamental design for a beer tap handle, as shown.
